POSTAL SCALE

Dana W. Mox, Glenview, Ill., assignor to Hanson Scale Company, a corporation of Illinois

Filed Dec. 9, 1959, Ser. No. 58,603

Term of patent 14 years

(Cl. D52—10)

FIG.1

The undisclosed side of the postal scale is substantially the same in appearance as the side shown.

I claim:

The ornamental design for a postal scale, as shown and described.
